UNITED STATES PATENT OFFICE

AARON MARGULIS, OF BROOKLYN, NEW YORK

SASH CONSTRUCTION

Application filed July 21, 1928. Serial No. 294,461.

This invention relates to sash constructions and in particular to the type which is adapted for the cleaning of the windows without the necessity of getting outside the window.

- 5 A particular object of the invention is to provide a window sash construction which is supported by suitable spring strips arranged to be supported on a spring roller to permit easy movement of the sashes.
- 10 A still further particular object of the invention is to provide a tongue and groove strip between the sashes and slide pieces secured thereto which will permit the sashes to be moved pivotally in the sash frame so
- 15 that both sides of the window may be cleaned.

A still further object of the invention is to provide tongue and groove connection between the slide piece and the sash so that the windows will be weather-proof.

- 20 To enable others skilled in the art to fully comprehend the underlying features of my invention that they may embody the same in the various modifications in structure and relation contemplated, drawings depicting a
- 25 preferred form have been annexed as a part of this disclosure and in such drawings, similar reference characters denote corresponding parts throughout all the views, of which,

Figure 1 is a view in front elevation of a

30 window sash construction, a part thereof being shown in section to disclose the spring housing and method of supporting the sashes within the frame.

Figure 2 is a view in end elevation of the

35 sashes, the lower one being shown in its pivotal position.

Figure 3 is an enlarged, fragmentary section of the upper end of the sash frame at one side thereof illustrating the spring housing

40 and method of attaching the end of the spring strip to the slide piece, and

Figure 4 is a plan view in section taken through one side of the sash and sash frame and illustrating how the tongue and groove

45 members are applied to the slide piece and sash to permit pivotal operation of the latter.

Referring to the drawings in detail, 5 indicates a sash frame of the usual construction which is provided adjacent its upper ends and at opposite sides thereof with openings 6 in

which are disposed, the spring housings 7. These housings are provided with extensions 8 which fit into the sash frame 5 in an undercut slot and are retained in position through the medium of the screws 9.

55

In view of the fact that both sashes are of identically the same construction and both sides of the window are also of identically the same construction, it is believed necessary to only describe in particular, one set of the operating mechanism. The lower sash is indicated by the numeral 10 and the upper sash by the numeral 11, the sashes consisting of the usual frame piece 12 and glass 13 and the side edges of the sash frame piece 12 are covered by a longitudinal groove piece 13a made of metal, the groove therein being indicated by the numeral 14 and being of a suitable depth to accommodate snugly the tongue 15 formed in the tongue strip 16 which is of identically the same construction as the groove strip 13, the edges of each being turned over and secured in any manner to the side of the sash piece 12 and slide piece 18. The slide piece is of the same length as the sash piece 12, and as before noted is provided at one of its edges with the tongue strip 16. The slide piece is further provided with a recess 19 from which extends a bore 20, this bore 20 connecting the recess 19 with the tongue strip 16 and being arranged to accommodate a coil spring 21 which is positioned about a bolt 22 which is threaded as at one end 23 into the sash piece 12, the opposite end thereof being threaded to receive the cap nut 24 against which the outer end of the spring 21 presses, it being quite evident that this cap nut may be used to adjust the tension on the spring and the lower end of the spring bearing against the tongue portion of the strip 16 will have a tendency to maintain it in its extended position under all conditions.

The metal of which the tongue and groove strips are made may be more or less of a resilient nature so that the longitudinal tongue 15 may snap out of and into the groove 14 when the frame piece 12 is swung about the pivot point, namely, the bolt 22 one of each of which is positioned at opposite sides of the center of the upper and lower sashes, the

90

95

100

outer ends of the bolt 22 is provided with an eye 24 which is engaged by the end of the spring strip 25, the opposite end of the spring strip being secured to a suitable spring roller 26 through the medium of a screw 27, the roller itself being mounted on an axle 28 which is journaled in any suitable manner in the side walls of the spring housing 7. It is quite evident also that the spring 21 permits movement of the slide piece into the slot 29 of the sash frame construction. These slots being provided for travel of the sashes.

It is also evident that these slide pieces may have free movement in the grooves 29 when the sashes are to be raised or lowered.

The spring strip 25 is made of spring metal which will have a tendency to wind up the spring roller 26 when the window sash is raised. In this respect, the usual counter-weights are dispensed with and the necessity for frequent replacement of the worn out sash cords is eliminated.

It is also quite evident that with the spring connection of the slide piece and sash frame piece 12 that the two will be securely joined together and will prevent the admission of any moisture or cold air through the construction. These grooves and tongue strips act as weather strips when the sashes are in their normal position.

It is quite evident also, that by this construction, the sashes may be revolved about their pivot point and the windows may be readily cleaned without the necessity of the cleaner getting out upon the window sill.

It is also evident that in a construction of this character, the parts may be applied to window sashes in existence, it being simply necessary to remove the sash cord pulleys and substitute the spring housing and to cut the sash frames to provide slide pieces which are joined in the manner indicated to provide pivotal joining of the sashes.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claim.

Having thus described my invention what I claim as new and desire to secure by United States Letters Patent is:-

A window sash construction, a channeled sash frame, a sash, a grooved strip covering an edge of said sash and extending the entire length of said edge, a slide piece having an opening therein at substantially the horizontal center of the sash, a fluted strip covering an edge of the slide and extending the entire length of said edge, the flute being arranged to seat in the groove of said sash strip, a bolt having a hook end secured in said sash and

passing into the opening of the slide piece, said hook being arranged to receive the end of a supporting member and to constitute a pivot for the sash, a nut threaded to said bolt, and a tension spring on the bolt positioned between the fluted slide strip and said nut for yieldably maintaining the sash and slide strip in contact.

In testimony whereof I affix my signature.
